DESIGN FOR A SURFACE TREATING MACHINE

Louis Vavrik, Rossford, and Kenneth C. Atkin,
Toledo, Ohio, assignors to The American Floor
Surfacing Machine Company, Toledo, Ohio, a
corporation of Ohio

Application April 22, 1942, Serial No. 106,658

Term of patent 14 years

To all whom it may concern:

Be it known that we, Louis Vavrik and Kenneth C. Atkin, citizens of the United States and residents of Rossford, county of Wood, State of Ohio, and Toledo, county of Lucas, State of Ohio, respectively, have invented a new, original, and ornamental Design for a Surface Treating Machine, of which the following is a specification, reference being had to the accompanying drawing, forming a part thereof.

In the drawing, Figs. 1 and 2 are front per-

spective views taken from opposite sides of a surface treating machine, showing our new design, and Fig. 3 is a rear elevation thereof.

The dominant features of our design are shown in solid lines on the drawing.

We claim:

The ornamental design for a surface treating machine, substantially as shown and described.
